(57) **CLAIM**

I claim the ornamental design for a display screen with animated graphical user interface, as shown and described.

DESCRIPTION

FIG. 1 is a front view of a display screen with animated graphical user interface showing our new design;

FIG. 2 is front view of a second image thereof; and,

FIG. 3 is front view of a third image thereof.

In the drawings, the broken lines are for the purpose of illustrating portions of a display screen with animated graphical user interface and environmental structure that form no part of the claimed design.
